(57) **CLAIM**

The ornamental design for a pinch light with attachment mechanism, as shown and described.

DESCRIPTION

FIG. 1 is a front elevational view of a first embodiment of a pinch light with attachment mechanism; the broken lines show unclaimed features of my design.

FIG. 2 is a back elevational view of FIG. 1.

FIG. 3 is a right side elevational view of FIG. 1, the left side being a mirror image of FIG. 3.

FIG. 4 is a top plan view of FIG. 1.

FIG. 5 is a bottom plan view of FIG. 1.

FIG. 6 top isometric view of the pinch light of FIG. 1, with the flexible attachment mechanism shown bent into a possible condition of use.

FIG. 7 is a back elevational view of a second embodiment of a pinch light with attachment mechanism; the broken lines show unclaimed features of my design.

FIG. 8 is front elevational of FIG. 7.

FIG. 9 is a right side view of FIG. 7, the left side being a mirror image of FIG. 9.

FIG. 10 is a top plan view of FIG. 7.

FIG. 11 is a bottom plan view of FIG. 1; and,

FIG. 12 is a top isometric view of FIG. 7, with the flexible attachment mechanism shown bent into a possible condition of use.

The features shown in broken lines in the drawing depict environmental subject matter only and form no part of the claimed design.
